(57) **CLAIM**

The ornamental design for a vanity, as shown and described.

DESCRIPTION

In a preferred embodiment, the nature of this product is a vanity such as can be used to support a lavatory.

FIG. 1 is a left, top, front perspective view of a vanity embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a rear elevational view thereof; and,

FIG. 6 is a bottom plan view thereof.

The broken line representations of shelf and tray environment in FIGS. 1, 3 and 4-6, trim structure in FIGS. 1-5, and an opening in FIGS. 1 and 2, are for the purpose of illustration only, and form no part of the claimed design.
